UNITED STATES PATENT OFFICE.

JAMES C. SHOUP, OF NEW YORK, N. Y., ASSIGNOR TO HENRIETTA
PREWETT SHOUP, OF NEW YORK, N. Y.

AUTOGRAPHIC REGISTER.

SPECIFICATION forming part of Letters Patent No. 707,458, dated **August 19, 1902.**

Application filed July 20, 1891. Serial No. 400,098. (No model.)

To all whom it may concern:

Be it known that I, JAMES C. SHOUP, a citizen of the United States, residing in the city, county, and State of New York, have invented 5 certain new and useful Improvements in Auto-graphic Registers; and I do hereby declare that the following is a full, clear, and exact description of the invention, such as will enable others skilled in the art to which it appertains 10 to make and use the same.

My invention relates to improvements in autographic registers of the general character described in my Patent No. 286,560, dated October 9, 1883.

15 The invention consists in certain novel features and combinations hereinafter described and claimed.

In the drawings forming a part of this specification, Figure 1 is a longitudinal section 20 through the apparatus. Fig. 2 is a similar section of a segment, showing the casing open and a part swung outward for adjustment of paper-rolls. Fig. 3 is a transverse section on the line xx of Fig. 1, and Fig. 4 shows in perspective a flexibly - mounted roll - carrying frame. 25

A is the main casing and frame of the machine, and A' a supplementary part jointed to the main part at *a*, so that it may be thrown up into the position shown in Fig. 2 for convenience of inserting and removing the paper-rolls.

B is a lid or cover for the main frame and carries a frame or border b for embracing the tablet and a hood b' for inclosing the upper grip-roll. This lid is jointed to the frame at a' .

C is the tablet mounted in and supported by the hinged part A' of the frame.

40 D D are dispensing-reels, from which strips of paper are led over the tablets C and c to the primary gripping-rolls d d'. D' is also a dispensing-reel, from which a strip of paper is led over the small or supplemental tablet c, past the roll d' and a guide-roll 1 to a storage-roll 2.

E is a frame mounted to vibrate in the main frame on a rod or bar e. This frame is provided with bearing notches or sockets 3 3 for supporting the storage-roll 2. A spring F, through frame E, presses roll 2 upward against

or toward the guide-roll 1. Said rolls 1 and 2 therefore operate as secondary gripping-rolls to draw the storage paper strip forward. The roll d' has a spindle projecting through the frame, to which is attached a crank 4, and through this roll and roll d the issue-strips from rolls D D are fed forward over the tablets and out of the machine. The spindle of roll d' also carries a pinion 5, (shown in dotted lines in Fig. 1,) which intergears with spur-gear 6, through which latter roll 1 is operated, and through the latter the spring-pressed roll 2 is also turned, and the two together draw the paper from D' forward, the roll 2 becoming a storage-roll.

It will be observed that the roll d' is the driving-roll of the pair of rolls d and d' and that roll 1 is the driving-roll of the pair 1 and 2, and as pinion 5 is smaller than spur-gear 6 the strips from reels D D will move at greater speed than strip from reel D' . It will also be observed that the length of strip wound on roll 2 will be uniform with a given movement of the crank, notwithstanding the roll 2 constantly increases in size as the paper is rolled up. The spring F yields sufficiently to accommodate a storage-roll of reasonable size, or such as is required for one day's transactions. A ratchet 7 is connected with the spindle of roll d' , with which a pawl 8 interlocks to prevent backward movement of the rolls.

H H are spring-latches for locking the lid and border-frame down upon the main eas- 85 ing. These latches are mounted on a shaft or rod 9, from which projects an arm 10, which interlocks with another arm 11 on rock-shaft 12. The rock-shaft 12 carries teeth or punches 13, which punch holes in the record-strip 90 from reel D' whenever the latch H is operated to unlock the lid and permit access to the interior of the apparatus. The roll d' is grooved, as shown in dotted lines, Fig. 3, to permit the teeth to puncture the paper strip. 95 The rod or shaft 9 also carries at a convenient point between its ends a second latch 14 for locking the front plate of the case.

I I are spring tension-brakes, and K is a trough alongside the upper part of the case and opposite the tablet for holding a roll of manifolding fabric, said roll being made up

of two strips of manifolding fabric wound thereon, as shown in Fig. 3. Said roll is tensioned as in same figure by a strap or lid pivoted to the trough K. The strips of fabric are 5 passed out of an opening shown in the trough K—one between the upper strips of paper over the tablets C and c and the other between the lower strips of paper. A shield or guide-plate 15 is arranged adjacent to roll d' 10 to guide the paper alongside said roll.

Having now described my invention, what I claim is—

1. In an autographic register, a two-part writing-tablet and a plurality of reels bearing strips of paper, in combination with primary gripping-rolls for feeding strips of paper over the tablet out of the machine, and secondary gripping-rolls located below and actuated by the primary rolls for feeding a 20 strip of paper over a portion of the tablet to a storage-roll.

2. In an autographic register, a two-part writing-tablet and a plurality of reels bearing strips of paper, in combination with primary gripping-rolls for feeding strips of paper over the tablet out of the machine, secondary gripping-rolls below the primary rolls for feeding a strip of paper over a portion of the tablet to a storage-roll and reducing-gearing between 25 the primary and the secondary rolls.

3. In an autographic apparatus, divided in two parts hinged together, a tablet, a pair of gripping-rolls supported in one part in combination with a second pair of gripping-rolls, 35 having one roll supported in the part carrying the first pair of gripping-rolls, and one of the gripping-rolls forming the second pair supported in the other part of the casing.

4. In an autographic register, a stationary 40 portion having mounted therein a spring-pressed frame carrying a storage-roll, and a series of dispensing-reels, in combination with a movable portion carrying a two-part writing-tablet and a supplemental dispensing-reel,

mechanism for feeding the paper from the 45 reels over the writing-tablet without the machine, and a guide-roll for feeding the paper from the supplemental reel over a portion of the tablet and winding it upon the storage-reel. 50

5. In an autographic register employing a check-strip and a record-strip, the combination of a tablet-plate adapted to have the check-strip passed over the entire length of it and provided with an opening through which 55 the record-strip may be passed and led over only a portion of the plate, and a transfer-sheet between the two strips, whereby only a part of the matter written upon the check-strip will be duplicated upon the record-strip. 60

6. In an autographic register employing a check-strip and a record-strip, the combination of a tablet-plate adapted to have the check-strip passed over the entire length of it and provided near one end with a transverse 65 slot through which the record-strip may be passed from the under side of the plate and led over only a portion of the plate, and a transfer-sheet between the strips, whereby only a part of the matter written upon the 70 check-strip will be duplicated upon the record-strip.

7. In an autographic register employing a check-strip and a record-strip, the combination of a tablet-plate adapted to have the 75 check-strip passed over the entire length of it and provided with an opening through which the record-strip may be passed and led over only a portion of the plate, a transfer-sheet between the strips, and a storage-reel for 80 winding up the record-strip, substantially as described.

In testimony whereof I affix my signature in the presence of two witnesses.

JAMES C. SHOUP.
